Coffey, Normandy, Mo.

Application May 21, 1941, Serial No. 394,418

3 Claims. (Cl. 60—54)

This invention relates to fluid drives and particularly to those having a pair of vane or turbine wheels, together defining a chamber containing oil or similar operating fluid. Previous devices of this character have been subject to the difficulty caused by the dragging of the turbine wheels at low speeds, whereas, it is desirable that the wheels become completely free and disengaged when the speed of rotation drops below a predetermined rate. Attempts have been made to eliminate this dragging by withdrawing the fluid from between the turbine wheels, but devices for this purpose have not been entirely successful, and it is an object of this invention to produce a new and improved fluid drive, together with a new and improved method and means of withdrawing the fluid from between the turbine wheels.

Other objects and advantages will be apparent upon consideration of the following description, claims, and accompanying drawing.

Referring to the drawing,

Figure 1 is a somewhat diagrammatic, longitudinal section of our improved fluid drive showing the parts in the positions which they occupy at high speeds when the clutch or drive is engaged.

Figure 2 is a view similar to Figure 1, but showing the parts in the positions they occupy when the drive is disengaged.

Figure 3 is a cross sectional view taken along the line 3—3 of Figure 1.

The reference numeral 1 indicates a housing which is attached to a prime mover (not shown) which may be an automotive internal combustion engine. It will be understood that the engine is attached at the left of Figures 1 and 2, while the transmission housing 2 is at the opposite end of the housing. Power shaft 3 is connected to the engine and carries a rotary main casing 4 which contains the driving impeller 5 and also the driven turbine 6. These rotors are of known construction, but for a more detailed showing, reference is had to United States Patents No. 1,199,359, 1,199,360, 1,199,364 and 2,179,520.

The impeller 5 is attached to a flange 7 on the end of the shaft 3 and rotates as a unit with the shaft and the housing 4, while the turbine 6 is rotatably mounted in the housing 4 and in the end of the shaft 3 by means of suitable ball bearings 8 and 9, respectively. A packing gland 10 is provided to prevent the escape of oil or other fluid from the rotor housing, it being understood that the turbine 6 is enclosed by a

cover member 11 attached to the rotor housing 4. The rotor housing contains a plurality of float chambers or cylinders 12 in which are mounted the floats or pistons 13. These floats are not necessarily fitted to the members 12 in such a manner as to prevent leakage, as the principle of operation is not dependent on the prevention of leakage at this point.

The pistons 13 are connected to a slidable member 14 by means of connecting rods 15 having wrist pins at 16 and 17, respectively. The member 14 is slidable on the shaft 3, but keys 18 may be provided to prevent relative rotation between pistons 13 and the shaft, if desired. A strong spring 19 is mounted between the flange 7 at the end of the shaft 3 and the slidable member 14. This spring is strong enough to overcome the centrifugal force of the pistons 13 when the operating speed is below the speed at which the clutch or drive is desired to be engaged.

It will be understood that the housing is supplied with at least sufficient oil to cause the impeller 5 and turbine 6 to be completely filled when the parts are in the position shown in Figure 1. However, when the pistons 13 are withdrawn, the capacity of the cylinders 12 is sufficient to receive substantially all the oil contained in the rotor chambers so that the oil may be completely withdrawn therefrom.

The chambers or cylinders 12 are located slightly more distantly from the center of rotation than the rotor or baffle chambers 5 and 6, so that the oil will naturally tend to flow from the rotor chambers to the chambers 12 by centrifugal force whenever the pistons 13 are withdrawn, it being understood that suitable passages 20 are formed to connect the periphery of the turbine housing with the chambers 12.

In operation, the spring 19 holds the pistons or floats 13 in the positions shown in Figure 2 while the device is at rest and until the speed of rotation imparts sufficient centrifugal force to the floats 13 to cause them to move outwardly to the positions shown in Figure 1, thereby displacing the oil from the float chambers 12 into the rotor housing. The speed of rotation at which the rotor housing is filled may be controlled by the strength of the spring 19 and by the weight of the pistons or floats 13, but for normal automotive use the rotor housing should be filled at speeds between 400 and 500 R. P. M. When the rotor housing is filled, the drive is engaged, although a complete engagement of the drive does not occur until the speed is still further in-

creased. It is also understood that some slippage is always necessary with this type of drive.

While the term "piston" has been used in connection with the members 18 and while these members should be guided with accuracy by the walls of the chambers or cylinders 12 to maintain a proper balance of the device, it should be understood that some leakage past these pistons is necessary to prevent the retention of oil in the inner part of the housing while the device is operated. Normally sufficient leakage past the walls of the pistons to take care of this will occur, but the skirts 21 of the pistons should be provided with drain holes 22 to prevent oil from being retained inside the pistons.

We claim:

1. In a fluid drive mechanism, a rotary housing member, means forming a rotor chamber in said housing, and an impeller in said chamber, means forming a fluid chamber in said housing, at least a portion of said chamber being more distantly spaced from the axis than the main portion of the rotor chamber whereby operating fluid will tend to flow from said rotor chamber to said fluid chamber through a conduit connected to the outer periphery of the rotor chamber by centrifugal force, a fluid displacing device having a volume equal to the volume of the fluid which is to be displaced movable into said fluid chamber to cause fluid to be forced into said rotor chamber and withdrawable from said fluid chamber to permit the return of fluid from said rotor chamber to said fluid chamber by centrifugal force.

5 gal action, and speed responsive means for causing said fluid displacing device to be moved into said fluid chamber when a predetermined speed is exceeded and withdrawn therefrom at lower speeds.

10 2. In a fluid drive mechanism, a rotor chamber containing an impeller and a turbine, a fluid receiving chamber mounted more distantly from the axis of rotation than said rotor chamber is mounted, and means for positively urging the operating fluid from one of said chambers to the other in accordance with the speed of rotation through a conduit connected to the outer periphery of the rotor chamber, said means comprising fluid displacing members having a combined volume equal to the volume of the fluid which is all the oil contained in the rotor chambers.

15 3. In a fluid drive mechanism, a rotor chamber containing an impeller and a turbine, a fluid receiving chamber mounted more distantly from the axis of rotation than said rotor chamber is mounted, and means for shifting the operating fluid from one of said chambers to the other in accordance with the speed of rotation through a conduit connected to the outer periphery of the rotor chamber, said means including a plurality of radially movable fluid displacing members having a combined volume equal to the volume of all of the fluid contained in the rotor chambers constructed and arranged to be moved by centrifugal force into said fluid receiving chamber.
